UNITED STATES PATENT OFFICE

100,016

DESIGN FOR A CANDLESTICK OR SIMILAR ARTICLE

Leonard A. Goldsmith, Chicago, Ill., assignor to Pearl T. Goldsmith, Chicago, Ill.

Application April 24, 1936, Serial No. 62,284

Term of patent 14 years

To all whom it may concern:

Be it known that I, Leonard A. Goldsmith, a citizen of the United States and a resident of the city of Chicago, county of Cook, and State of Illinois, have invented a new, original, and ornamental Design for a Candle Stick or Similar Article, of which the following is a specification, reference being had to the accompanying drawing, forming a part thereof.

On the drawing:

The figure is an isometric view of the candle stick or similar article, showing my new design.

I claim:

The ornamental design for a candle stick or similar article as shown.

LEONARD A. GOLDSMITH.
